General Steel Industries, Inc., Granite City, Ill., a cor-
poration of Delaware

Filed Dec. 29, 1965, Ser. No. 365

Term of patent 14 years

(Cl. D66—1)

FIG. 3

FIG. 1

FIG. 2a

FIG. 2b

FIG. 2c

FIG. 1 is a perspective view of a railway passenger train showing my new design.

FIGS. 2a, 2b and 2c are side views of the train.

FIG. 3 is a rear end view of the train.

The sides are substantially mirror images of each other. The dominant features of my design reside in the portions shown in full lines.

I claim:

The ornamental design for a railway passenger train, substantially as shown and described.
